UNITED STATES PATENT OFFICE.

SAMUEL L. MYERS, OF TEXARKANA, ARKANSAS.

FOUNTAIN-COMB.

SPECIFICATION forming part of Letters Patent No. 678,004, dated July 9, 1901.

Application filed August 18, 1900. Serial No. 27,333. (No model.)

To all whom it may concern:

Be it known that I, SAMUEL L. MYERS, a citizen of the United States, residing at Texarkana, in the county of Miller and State of Arkansas, have invented a new and useful 5 Fountain-Comb, of which the following is a specification.

This invention relates to improvements in fountain-combs; and the object is to provide 10 a device for the purpose of applying medicinal preparations in liquid form to the scalp, the device operating in a very effective and convenient manner.

With this object in view the invention consists in the novel details of construction hereinafter fully described, and particularly pointed out in the claim, and clearly illustrated by the accompanying drawings, in which—

Figure 1 is a perspective view of a fountain- 26 comb embodying my invention. Fig. 2 is a vertical longitudinal sectional view of the same.

Referring now more particularly to the drawings, A designates a liquid-containing receptacle which may be of any desired contour, 25 formed of any preferred material, the same in the present instance having an opening in one of its side walls and an ingress-opening in its upper wall, which opening is surrounded by a band or collar B and provided with an internally-screw-threaded receiving plug or stopper C. The opening in the side wall of the receptacle is surrounded on the exterior thereof with a hood or collar C, provided with a screw-threaded opening in line with the opening in the receptacle, and in this screw-threaded hood a valve-casing D is secured, containing a valve E. Connected with this valve-case is a bulb F, having a valve-casing G at its opposite end 40 containing a valve H. I designates a pipe or tube communicating at one end with the valve-casing E and extending upwardly in the receptacle and through the band thereof and thence downwardly on the exterior of 45 said receptacle. The pipe at its lower end carries a hollow semicircular head J. Inside of the receptacle-pipe I is provided with an open-ended branch pipe K, through which the liquid is drawn when the bulb is compressed.

L designates a plurality of teeth formed in-

tegral at their upper ends with a semicircular hollow head M, which is united to the hollow head J, forming a chamber at the lower end of pipe I. Each of the teeth is provided with 55 a passage N, opening at its lower end through the tooth and at its upper end communicating with the chamber.

O designates a brace which is secured at one end to the head and extends beneath the 60 receptacle and at its opposite end is connected with the teeth.

P designates the handle, which is of convenient form to be grasped by the hand, said handle at its inner end being secured to the 65 collar of the receptacle and to the hood and at its opposite end to the valve-casing at that end of the bulb. This handle is provided with lateral wings Q, which extend at the sides of the bulb. 70

In operation the receptacle is filled with the preparation to be applied to the scalp and the teeth are drawn through the hair, the bulb being pressed, as in ordinary atomizers, which causes the liquid to be forced through 75 the teeth to the scalp.

Having thus fully described my invention, what I claim as new, and desire to secure by Letters Patent, is—

A device of the character described comprising a receptacle provided with a filling-opening, a removable cap closing said opening, a pipe positioned in said receptacle and projecting at its ends through the front and rear walls thereof and having a branch pipe 80 extending downwardly in the receptacle, a handle secured to the rear side of the receptacle, a bulb secured beneath said handle and communicating at its outlet end with the projecting end of the pipe and having an inlet 85 at its opposite end, valves controlling said inlet and outlet, a tubular head positioned upon the front side of the receptacle and communicating with the other end of the pipe, and a plurality of teeth depending from said 90 head and having passages extending therethrough and communicating with the head, substantially as described.

SAMUEL L. MYERS.
